UNITED STATES PATENT OFFICE

THOMAS J. PETTIT AND C. CHRISTIAN RUSS, OF SAN FRANCISCO, CAL.

DESIGN FOR PRINTING-TYPES.

Specification forming part of Design No. **11.538**, dated December 9, 1879; application filed October 6, 1879.
[Term of patent 3½ years.]

To all whom it may concern:

Be it known that we, THOMAS J. PETTIT and C. CHRISTIAN RUSS, both of the city and county of San Francisco, in the State of California, have invented and originated a new and useful Design for Printing - Types, or letters for printing posters and other work of similar character, of which the following is a full, clear, and exact description, reference being had to the accompanying drawing, making part of this specification.

As illustrated in the accompanying drawing, our design consists, essentially, in forming the top and bottom extremities of the letters with enlargements *b b*, of ovate shape, terminating in an acute projecting point, and in adding thereto, at the base of each enlargement, the attached and projecting ornaments *e e*.

The drawing shows two specimen letters, from which others of the alphabet can be formed according to the principles of our design, by any one skilled in the art.

The formation of the letter A is applicable to all letters formed equally about an axis, *xx*, and the letter B to letters formed unequally about a like axis, *x' x'*.

We form the upright members or stems in all the letters of curved lines, *aa*, which, both at top and bottom of the stem, are spread outward to produce an enlargement, *b*, of an ovate shape, and are then carried inward to an acute projecting point, *c*. This ovate *b*, with its acute point *c*, forms the extremity of the letter both at top and at bottom. In all equally-balanced letters this acuminate shape at top and bottom is equally disposed about a central vertical line, *y y*, as in the letter A of the drawing; but in those letters unequally formed about the vertical axis, as at *x' x'*, letter B, the acute terminals *c* are carried to one side of the center of the letter, so that they project at top and bottom nearly over the upright member or stem of the letter.

At the base of each ovate *b*, and where the curved lines of the stem begin to diverge and form this enlargement, we place the attached ornaments *e e* upon both sides of the upright stem. These ornaments project from but follow the general outline or contour of the letter. They are also disposed within the central spaces or openings of the oval letters, as well as those composed of upright stems and ovals, as seen in the letter B of the drawing.

In the stem or upright member of the letter, and upon a horizontal centerline, *zz*, we produce the curved lines *aa* outwardly, and then carry them inward to form the return angular faces *ff*, which are made to terminate in a point or in a curved or circular recess, *g*. This enlargement *f g*, at the center of the stem, may be used or not, as desired, leaving the standards or stems of the letter straight, while the other shaped portions will have the usual form at those points.

In the accompanying drawing we show our design as applied to a type for printing posters and other large work, in which the letter is cut or formed in a block of wood or metal in intaglio, leaving the surrounding surface to receive the impression.

What we claim as our invention is—

A design for a printing-type or letter, in which the body of the letter at top and bottom is composed of an enlarged ovate-shaped terminal, *b b*, with acute projecting point *c*, and with the attached and projecting ornaments *e e*, substantially in the manner described.

Witness our hands and seals.
